CLAIM

The ornamental design for a cosmetics applicator with cap, as shown and described.

DESCRIPTION

FIG. 1 is a perspective view of a cosmetics applicator with cap;

FIG. 2 is a front view of the cosmetics applicator with cap from FIG. 1;

FIG. 3 is a view of the left side of the cosmetics applicator with cap from FIG. 1;

FIG. 4 is a rear view of the cosmetics applicator with cap from FIG. 1;

FIG. 5 is a view of the right side of the cosmetics applicator with cap from FIG. 1;

FIG. 6 is a top view of the cosmetics applicator with cap from FIG. 1; and,

FIG. 7 is a bottom view of the cosmetics applicator with cap from FIG. 1.

The evenly broken lines in FIGS. 1 and 2 depict portions of the cosmetics applicator with cap that form no part of the claimed design. The dashed-dot broken line and area within in FIGS. 1 and 2 depicts a boundary of the cosmetics applicator with cap that forms no part of the claimed design. None of the broken lines form part of the claimed design.
